CLAIM

The ornamental design for a footwear, as shown and described.

DESCRIPTION

FIG. 1 is a front, top and right side perspective view of a footwear according to the new design, the portion shown in broken lines forming no part of the claimed design; FIG. 2 is a right side elevation view of the footwear of FIG. 1;

FIG. 3 is a left side elevation view of the footwear of FIG. 1;

FIG. 4 is a front side elevation view of the footwear of FIG. 1;

FIG. 5 is a back side elevation view of the footwear of FIG. 1;

FIG. 6 is a top plan view of the footwear of FIG. 1;

FIG. 7 is a bottom plan view of the footwear of FIG. 1; and, FIG. 8 is a back, bottom, and left side perspective view of the footwear of FIG. 1.

The broken lines in the drawings show portions that form no part of the claimed design. The dot-dash lines in the drawings represent the boundary of the claimed design and form no part thereof.

1 Claim, 8 Drawing Sheets
